ANIMATED DISPLAY

Fred Hotchner, Los Angeles, Calif.

Application November 24, 1945, Serial No. 630,657

14 Claims. (Cl. 40—139)

1

This invention relates to animated displays applicable in the production of a wide variety of types of indoor and outdoor signs, exhibits, bulletin boards and decorative installations. It provides such devices constructed to exhibit effects of motion or animation along character, inscription or decorative outlines to beautify their appearance, enhance their attractiveness and increase their decorative and advertising value over that of prior art devices.

Display effects simulating motion at relatively high speed and extending for considerable distances over the backgrounds of the displays are produced by the operation of very simple apparatus in which the moving parts are displaced for very short distances and move at relatively low speed, thus making for simple, low cost and rugged devices which consume little power and operate free from mechanical trouble under severe service conditions.

The invention provides for the centralization of the driving units in a single or very few locations readily accessible for inspection and maintenance. The moving parts over the backgrounds are light and securely held and free from hazard to persons when the displays are installed over traveled locations. The invention may also be practiced by the completion of non-animated displays already in use by the addition thereto at very moderate cost of the mechanical elements peculiar to my device to produce animated displays.

The invention makes use of vibratile elements coupled one to the next in series extending along feature outlines over the backgrounds of display devices. These elements are constructed and mounted so that, as they vibrate, they variously modulate the view of the corresponding portions of the feature outlines. They are connected to each other in such manner that the vibration of one element is transmitted to successive elements along the series according to the laws of elastic wave motion. For this reason I have termed the series "elastic wave transmission lines" and have described the operation of the devices in the nomenclature of physics.

The invention is embodied in three species distinguished from each other by the manner in which devices built thereaccording operate to modulate the view of the feature outlines of the displays.

In the first species the observed animation effect is due to the direct view of the moving vibratile elements as they oscillate over their respective portions of the display background

2

with which they are arranged to be in sharp contrast.

In the second species the animation effect is produced by the periodic exposure and concealment of short sections of an outline detail on the background by the oscillations of the vibratile elements thereacross in response to the elastic wave on the line.

In the third species of the invention the vibratile elements are of the refracting type, preferably including lenses spaced from the background at approximately focal distances. The transmission line is arranged so that the lenses oscillate across an outline detail on the background to modulate the view thereof and, by the aggregate of the movement of the various vibratile elements, produce a desired animation effect along the outline.

The various objects of the invention will be apparent in the following specification read in view of the drawings.

The invention is shown in certain preferred embodiments in the accompanying drawings in which the same reference numeral is used to indicate the same or the equivalent part throughout when used in several views. All mechanisms shown in connection with the disclosure of individual species are to be understood as applicable to all of the species of the invention in proper adaptation.

In the drawings:

Figure 1 is a front elevation of one half of a display board, of the general class of road side or roof signs, exhibiting a design, certain outline features of which are to be rendered in apparent animation when the device is in operation. Along the courses of these outlines are shown series of vibratile elements mechanically associated together in elastic wave transmission lines, shown in this view in the inactive condition with all elements in their medial positions. Because of the small scale, the fine detailing of the transmission lines is eliminated. This board is shown constructed according to the second species of the invention, but by slight modification of the detailing of the elements, according to the description below, it may be taken to represent the invention in all of its species. The blank central area is for the usual display copy.

Figure 2 is a front elevation of a vertical sign having an ornamental border, according to the second species of the invention. This view is also simplified as to the fine detailing of the lines.

Figures 3, 4 and 5 are front elevations of one vertical half of the sign of Figure 2 variously

modified to illustrate the animation effect produced by the invention in its three species in action. The elements of the transmission line are shown displaced in a sinuous line in each view illustrating the instantaneous appearance of a sine wave traveling in one direction along the line. The fine details of the transmission lines are omitted in these views because of the small scale.

Figure 3, illustrative of the invention in its first species in which the vibratile elements, finished to contrast sharply with the background, produce the observed animation by their own motion, shows the effect as being that of a sinuous wave moving along the border.

Figure 4 illustrates the invention in its second species, in which the vibratile elements produce the animation effect by the progressive exposure and concealment of portions of the outline painted on the background of the sign, the elements themselves preferably being finished to a minimum of contrast with the background surface proper. The effect produced is that of short sections of the straight outline on the background, separated by light areas, moving along the course of the border.

Figure 5 illustrates the invention in its third species, in which the vibratile elements are of the refracting type, producing the effect of motion along the border by variously modulating the view of the outline on the background as they oscillate thereacross in the special manner described below. In this construction also the effect is that of short spaced sections of the straight border following each other in a line.

Figure 6 is a sectional elevation through the background as indicated by the section line 6—6 in Figure 1, showing the various elements of a transmission line in the inactive condition with all elements in their medial positions. The view is shortened by the cut-out of the mid-section of the line.

Figure 7 is a sectional view of the motive unit taken as indicated by the section line 7—7 in Figure 6 in projected position with respect to that view. The crank and driving arm are shown moved to one extreme position corresponding to extreme displacement of the vibratile elements to better illustrate the mechanism.

Figure 8 is a projected sectional view of the resistance unit or wave damper at the opposite end of the line from the motive unit taken as indicated by the section line 8—8 in Figure 6. The rocker arm is in the medial position.

Figure 9 is a perspective view of one of the transmission lines shown in Figure 1, taken from a point of view in front of the plane of the drawing and in the direction indicated by the arrow A. The line is shown in the inactive condition with all elements in their medial positions. This view shows the line elements carrying surface finishes as required for the practice of the invention in the second species in the embodiment illustrated.

Figure 10 is an enlargement of the upper part of one of the elements in perspective illustrating the formation of the passage through the head of the element for the cable which formation provides the bearing point for the cable, against the member at the mid-point through the passage.

Figure 11 is a perspective view of a short section of the line including three elements showing them with surface finishes as required for the practice of the invention in the first species in the embodiment illustrated.

Figure 12 is a diagrammatic illustration in a

view transverse of the line showing the mode of vibration of the elements.

Figure 13 is a perspective view of a short section of a transmission line in which the head of the vibratile elements comprise lenses arranged with respect to the outline inscription on the background to produce the effect illustrated in Figure 5 according to the third species of the invention.

Figures 14 and 15 are diagrammatic illustrations of the optics of the operation of the invention in its third species.

Figure 16 is a cross sectional diagram of the modification of the invention in its third species in which the inscription outline to be animated comprises a luminous tube.

Figure 17 is a perspective view of two vibratile elements fragmented from a transmission line in a modification of the invention suitable for use in any species in which the elastic member of the vibrating couple comprises a rubber tube or the like.

Figure 18 is a perspective view of two transmission lines meeting at a sharp angle and coupled to each other by a link illustrative of a suitable means for effecting dynamic junctions between lines.

In Figure 1, the display board, indicated generally by numeral 1, is supported between decorative columns, such as indicated by 2, and is constructed according to any of the conventional practices. Usually these boards have backgrounds of sheet metal framed by wood or steel bars and provided with open bracing to the ground or other foundation. The typical constructions of the art are adequate for carrying the mechanism of my animation with little or no structural change or reenforcement. Ample access to the rear for reaching the drive mechanism is almost always readily had. In any event, provision can be easily made to reach all the apparatus from the front by suitable boxing or hand holes.

On this board is painted an ornamental design, indicated generally by numeral 3, certain outline features of which are to be rendered animated when the device is in operation. The display here shown is constructed according to the second species of the invention in which the outline on the background is exposed to view in a particular fashion by the displacement of the vibratile elements in response to waves on the transmission line. In this view the device is shown in the inactive condition, and therefore the lines of vibratile elements 4, 5 and 6 which animate the straight rays, which are indicated by 4', 5' and 6', are covering the lines representing these rays on the background. Likewise the lines of elements 7 and 8 cover the painted sinuous rays, which are indicated by 7' and 8', on the background.

These lines of vibratile elements are driven by the motors 9, as shown in Figure 6, positioned on the rear surface of the background, the only portions of which are visible from the front being the driving arms 10. In the embodiment of the invention used to produce continuous motion along the outlines I make use of dampers at the opposite ends of the lines, the function of which will be described below. These dampers 11 are also positioned on the rear surface with their driven arms 12 only visible from the front. A flexible cable extends from the motor to the damper connecting all of the vibratile elements and transmits the wave motion along the line. The fine details of this cable are not shown in

this view but are detailed in later described views. All of the exposed elements of the line, that is motor and damper arms, cables and the vibratile elements, are shown in the medial or inactive condition.

It is characteristic of this invention that the driving means may be conveniently located for electric supply wires and the service men. Typically in this illustration it is seen that, while animation is produced for considerable distances over the background, it is necessary to bring the electric wires only to the position of the motors at the upper left hand of the board. Furthermore, it is not necessary to provide an individual motor for each line of vibratile elements as any mechanical means suitable for the transmission of oscillation may be used to activate a number of lines of animation from a central motor at a convenient location.

In Figure 2 is shown a sign of the vertical type, indicated by 15, having a decorative border, generally indicated by 16, two vertical lines of which, indicated by 17 and 18, are to be rendered animated. The central area 13 is for display copy, painted on the background, outlined in lights, or otherwise delineated. The two lines of vibratile elements 19 and 20 are constructed according to the second species of the invention and are shown in the inactive condition and hence, they also cover the outlines 19' and 20' on the background which are to be rendered apparently in motion when the device is operating.

It is to be understood that the invention is not limited to the particular type of transmission line shown, as various other combinations of mass and elasticity in line elements capable of vibrating in response to elastic waves to modulate the view of or appearance of design outlines, may be arranged to carry out the purport of this invention within the broad language of the claims. Further, in the type of line shown various modifications may be made in the construction.

It is further to be understood that the invention is not limited to the means shown for establishing waves on the line, as various other known driving means may be utilized in carrying out the invention as claimed. For instance, an electric vibrator tuned to the frequency of the vibratile elements may be used to initiate the elastic waves. Or a tuned vibrator driven by a vane exposed to be moved by the wind may be used. The invention may be practiced with or without the use of wave damping means.

The transmission line illustrated is of the transverse vibration type having a series of vibratile elements 14, each independently resiliently mounted to a common support, in this case the bar 24. Each of the elements comprises a head 23 and an elastic arm 25. The weight of the head acting against the elasticity of the arm constitutes each element a vibrating couple. These elements are arranged in a line and coupled to each other by the cable 26. As the vibrations on the line are transmitted from one element to the next by transverse vibration, the cable need not be fastened to the individual elements if other means are provided, as in this case, to maintain the cable taut.

In Figure 10 one of the elements is shown enlarged with the passage 27, through which the cable passes, indicated partially by broken lines to show that it is wide at the ends 28 in the plane of vibration of the cable and narrow at the center 29 so as to constitute the central part of the

passage as the bearing point of the cable on the head 23. The free length of the cable from element to element is thus substantially the element spacing distance along the line, which arrangement permits of spacing the elements close to each other and still have sufficient free cable length to form a line of desirable characteristics.

This transmission line may be manufactured in a very practical form by molding it in a single 10 piece, including all of the component parts with the exception of the cable, from any of several resins or plastic materials on the market, one example being cellulose acetate. Several such materials are available, which in thin sections 15 are quite elastic to form the elastic arms, and in thicker sections have ample rigidity and mechanical strength to form the heads. Thus, the arms 25 may be cast of thin section, such as the oblong design shown in Figures 9 and 10, forming a very satisfactory elastic arm. By making use of thermoplastic material, it is quite simple to heat and bend the bar 24 to follow the courses of curved outlines of moderate curvature. An additional advantage of molded plastic construction is that color may be cast into the piece 20 itself to serve the purposes of the invention as regards the display effects as explained in connection with Figures 3 and 4, such coloring being very brilliant and permanent.

The transmission line is bolted to the background sheeting 30 by bolts 31. In application to display boards a number of such lines may 35 be operated together from a single motive unit by means of links, rods or cables. Individual lines may be bent to follow moderate curves. Sharp angles in outlines may be dealt with by coupling individual lines together by means of links as shown in the perspective view of Figure 18 in which two lines 32 and 33 are coupled by 30 the link 34 which is attached to the elements 35 and 36 by flexible coupling means, such as rubber blocks, at the points 37 and 38.

In Figure 6 a transmission line with a driving unit and a damping unit is shown in elevation. 45 The view is taken along a line of sight parallel to the background and shows the parts in front of the background and the parts in the rear. Of the various types of driving means which might be used I have chosen the positive drive, gear reduction, electric motor, which, since it drives through a crank, imposes a wave of constant amplitude and frequency on the line.

This unit includes the motor housing formed by the base casting 40, the housing shell 41 and the gear housing 42. The base casting has two integral ears 43 and 44 by means of which it is bolted to the rear surface of the background by the bolts 45. The unit is indicated generally by the numeral 9. An opening 46 through the background is provided to pass the drive arm 10 through to the front of the sign.

The high speed rotor 48 within the housing drives the crank 49 through the gear train 50. The drive arm 10, which is integral with the yoke frame 51, oscillates on the shaft 47. The lower cross bar of this frame, indicated by 52 is slotted to receive the spherical roller 53 on the crank pin 54.

The operation of the motor vibrates the adjacent vibratile element, which element vibrates the next element. Successive elements being vibrated one from another, wave motion along the line takes place with each element moving transverse of the feature outline being animated. The line constitutes a mechanical analog of an electric

transmission line, and may be designed by following the well known laws of wave motion.

Various types of wave motion may be established on this line, with corresponding variations in the final animation effects produced. When one end of the line is vibrated to produce wave motion along the line and means are provided to prevent the waves from being reflected back at the opposite end from the drive point the resulting motion is that of "unidirectional" waves on the line. The most desirable effect for general display purposes is the unidirectional travel, produced by this type of wave motion, which is had by complete absorption of the energy received at the end of the line opposite the driven end and the prevention of reflection of wave motion back to the driven end. This is accomplished by the use of a resistor or wave damper 11 provided with the driven arm 12 which, with the driving arm 10 of the motor, holds the cable 20 taut.

The damper, of the dash pot type includes the body 56 having the integral ears 67 by means of which it is bolted to the rear surface of the background by means of bolts 45. This body is in the form of an open shell which, together with the two end plates 57 and 58, forms a wedge shaped chamber in which the blade 59 oscillates, sweeping over the inside surfaces of the covers and the bottom wall 60 of the chamber. The blade is integral with the cylindrical member 61 which turns in the cylindrical seats 62 and 63 of the body and carries the driven arm 12 to which the cable is attached.

The blade 59 divides the chamber into two spaces 68 and 69, tending to force fluid out of one space and draw fluid into the other space as it oscillates. These two spaces are in communication with each other through the passages 70 and 71 and the needle valve 72. By adjustment of the valve the resistance to fluid flow between the spaces is varied. By variations in the properties of the fluid used, the capacity of the device to introduce a factor of resilience in the end of the line may be controlled. Generally a non-compressible fluid such as hydraulic brake fluid is preferred for furnishing pure resistive impedance at the end of the line.

In operation the damper is adjusted to introduce the desired impedance at the end of the line to maintain the type of wave motion desired. When a pure unidirectional wave is desired fairly close control to substantially prevent all reflection can be had to a practical degree. In practice, resort may be had to fixed impedances of a variety of types on the theory that an impedance value close enough to give satisfactory results may be set for a given line and installed with the line, or if results are not entirely satisfactory a quick change may be made at little cost. Thus adjustable wave dampers may be found to be unnecessary in practice.

For some purposes the wave damper may be eliminated, and the end of the line held to a fixed point or left free to vibrate. Different types of wave motion may thus be obtained, as for instance, "standing waves," or various combinations of standing waves and traveling waves.

In adaptation to display devices, transmission lines may extend in any desired direction over the backgrounds. They may be driven by individual motive units, or by suitable rod, links or cables, a number of lines may be driven from a single central power unit. By taking advantage of that feature of the invention, animation may

be provided extending for very considerable distances over backgrounds with the power supply being brought to but a single or a very few points, making for very economical construction.

By observing good engineering practice in the design of the lines they may be constructed to dissipate very little power to the background, thus making it entirely practicable to install these devices on boards and sign bodies of standard construction with little or no reinforcement. It is to be expected that a vibratory reaction will exist at the two ends of the line, but in any case this is very easily met and compensated for by the introduction of sufficient mass at those points.

Considering now the specific constructions of, and the effects produced by, the invention in its different species, we have reference now to Figures 3, 4 and 5 to show the effects produced, Figures 9 and 11 to show the surface finishes or coloration distinctive of the first and second species, and Figures 13 to 15 showing the construction of and principle of operation of the lenticular elements of the third species.

According to the invention in its first species, the animation effect observed is the aggregate effect of the direct view of the heads of the elements themselves as they oscillate. In order that the elements should be the distinctive feature of the exhibit and display their own movement, the exposed surface of each element should be finished to contrast sharply with the background. In Figure 11 this is shown by the surfaces 75 which are finished black to show against the background which is indicated as white in Figure 3. The background areas which lie immediately behind the elements when they are at rest, and which are here exposed at 76, 77 and 78 where the elements have swung to the sides, should be finished white.

Thus the effect observed is that of a sinuous line apparently moving as a wave along the border. Figure 3 shows the desired effect. Actually, of course, as each element moves to its extreme position it will expose one side of the resilient arm 25 to the front view and a portion of the support bar 24. In order to reduce the visibility of these surfaces, the sides of the arms should be finished white as indicated by 79 in Figure 11 and the exposed surface 80 of the support bar should be similarly finished. In Figure 12 one of the vibratile elements is shown in end elevation in the solid lines, and in one extreme position of its oscillation in broken lines, the surfaces finished as above being similarly indicated.

According to the second species of the invention, as illustrated in Figure 4, the effect observed is due to the various exposure and concealment of portions of an outline delineated on the background by the vibratile elements as they oscillate thereacross. The elements should thus be finished so that in themselves they are not noticeable. Thus, in Figure 9 I have shown the front surfaces 75 finished in white so as to merge into the background to view. The inscription outline 65 may be delineated by the support bar 24. Thus I have shown the surface 80 of this bar finished black to contrast sharply with the white background.

The animation effect produced by the device of this species is that of short sections of the outline on the background, separated by white sections, moving in one direction along the border. These sections are indicated in Figure 4 by 81, 82 and 83 where the vibratile elements have swung to one side or the other. At the sections

indicated by 84 and 85, the vibratile elements are concealing the border, and since they are finished to merge to view into the background, the border appears to be broken at these places. Since the sides of the resilient arms 25 are exposed when the elements are swung to the sides, these surfaces are finished in black as indicated by 79 in Figure 9.

The effects of the first and second species may be combined by appropriate variations of the 10 surface finish of the elements.

The invention in its third species, the effect of which is shown in Figure 5, utilizes vibratile elements of the refracting type, preferably in the form of elongated lenses, as shown in Figure 13. 15 The vibrating couple here consists of the mass in the lens 91 acting against the elasticity of the wire arm 90 which is securely held to the support bar 24. The lens is secured to the arm by the eye nut 92 through which the cable 26 passes. 20 The lenses constitute the mass members of the vibratile elements. They are secured at their central points to the wires by the eye nuts 92. The wire arm is used in this form of the transmission line to provide the least optical obstruction.

Since the wire is resilient in all directions the cable 26 is depended upon to prevent longitudinal displacement of the elements relative to each other and hence it should be soldered or clamped at each of the points 93 with the eye nuts. Otherwise the transmission lines of the invention in this species are similar to and are driven by the same devices as those of the other species.

In Figure 14 the optical arrangement of the lenses is shown. The inscription outline may, as a practical matter, consist of the surface finish of the support bar which is shown as black in Figure 13 to contrast with a white background. The lenses are preferably located at focal distance from this surface. When the element is in its medial position the entire surface of the lens will then appear black to a person directly in front. The angle to the field of view over which the lens will be seen as black will depend on the width of the inscription outline.

Thus, rays gather from the point *a* at one edge of the outline will be projected to the field of view in a beam included between the bracketed rays as indicated by *a'*, while rays gathered from the opposite edge of the outline at *b* will similarly be projected as indicated by *b'*. From all points in the field of view between the extreme rays of these two beams, the lens will appear dark. From all points outside of this region the lens will focus on or very close to the white background and will appear white.

As the lens swings to one side of center as shown in Figure 15 the focal point as regards a position in front of the sign shifts to the background, and hence the lens will appear white as seen under this condition. But from a point of view to one side of the sign, as indicated by *d* the focus will now be on the inscription outline, as at *e*, and the lens will appear dark. By making the focus sharp on the outline the change from dark to light will be practically simultaneous all over the surface of the lens. By making the inscription outline relatively narrow the effect is produced by a relatively slight displacement of the 70 lens.

Referring now to Figure 5 in which the effect desired is illustrated: Those sections of the line of lenses which are indicated by 95, 96 and 97 include lenses which are, from the point of view

directly in front of the sign, focusing on the background, and hence they appear white. The sections indicated by 98, 99 and 100 include lenses which are, in passing the central position, focusing on the inscription outline, and hence they appear black from a position directly in front of the sign. As the lenses oscillate back and forth in response to a unidirectional wave on the line, these dark and light sections will shift in appearance in the direction of the wave movement. Hence in the embodiment of the invention shown in this view, which includes means to maintain unidirectional waves, a traveling effect from the top to the bottom of the border will be produced. This effect will be clearly visible over a substantial angle to each side of the center of the field of view, depending, of course, on the dimensioning of the elements and the amount of displacement of the wave motion. Generally, a very slight movement of the elements is sufficient to produce a striking effect over a comparatively wide field.

The inscription outline may be illuminated by any of the known methods. Thus, by way of 25 illustration of the use of illuminated outlines to be animated by any of the species of the invention, I have shown in Figure 16 the use of a luminous tube 101 in connection with a transmission line of the third species. The lenses should come to focus approximately on the tube and certain mechanical modifications are called for to adapt the transmission line to this use. Thus, the support bar 24 is offset from the central position behind the tube to permit of the usual 30 tube supports, and the resilient arm 90 has been given a conformation as shown to avoid hitting the tube.

In the modification of the invention shown in Figure 17, the vibrating couple consists of the 40 combined mass of the head 23 and the rigid arm 102 acting against the elasticity of the soft rubber tube 103, which is cemented to the support rod 104, in torsion. A series of such tubes are cemented at intervals along the rod and studs 45 106, welded to the rod provide support from the background of the sign. Surrounding the periphery of the resilient tube and cemented to it is the metal tube 105 which carries the rigid arm 102 which carries the head 23.

50 It is to be understood that the invention is not limited to the embodiments shown, or in its application to the details of construction or arrangement of parts illustrated, since it is capable of other embodiments and of being carried out in various ways. Also, it is to be understood that the phraseology or terminology employed herein is for the purpose of description and not of limitation, and it is not intended to limit the invention claimed herein beyond the requirements of the prior art.

55 The terms "refracting" and "lenticular" are used to describe the optical properties, or formations producing optical effects, broadly embracing the modulation of the view of or appearance of the feature outlines of the display.

The term "common support" is used in the broad sense of including any relatively rigid support for the vibratile elements whether on the background proper or otherwise based, and when so used, any plurality of supports serving the same end.

The terms "inscription outline" and "outline" embrace any kind of inscription or lineation.

The term "vibratile element" as used in the 75 claims defines an element having an elastic part

and a part having mass which forms with said elastic part a vibrating couple characterized by a natural period of oscillation.

Having thus described my invention, what I claim is:

1. A display device including a background member across which the effect of an animated outline is to be produced, a series of vibratile elements contrasting in appearance to said background connected one to the next in an elastic wave transmission line by means through which the vibration of one element is transmitted to successive elements along the line as elastic wave motion, said transmission line extending along the course of said outline, each of said vibratile elements being formed to visibly oscillate across the corresponding portion of said background in response to wave motion along said transmission line, and means to impart wave motion to said transmission line to oscillate said vibratile elements and thereby produce the effect of animation therealong.

2. A display device including a background member across which the effect of an animated outline is to be produced, a series of vibratile elements contrasting in appearance to said background, each resiliently mounted to a common support and formed to visibly oscillate across said background in response to wave motion, said vibratile elements being connected one to the next in an elastic wave transmission line by means through which the vibration of one element is transmitted to successive elements along the line as elastic wave motion, said transmission line extending along the course of said outline, and means to impart wave motion to said transmission line to oscillate said vibratile elements and thereby produce the effect of animation therealong.

3. A display device including a background member across which the effect of an animated outline is to be produced, a series of vibratile elements contrasting in appearance to said background connected one to the next in an elastic wave transmission line by means through which the vibration of one element is transmitted to successive elements along the line as elastic wave motion, said transmission line extending along the course of said outline, each of which vibratile elements is adapted to visibly oscillate across the corresponding portion of said background in response to wave motion along said transmission line, means at one end of said transmission line to impart wave motion thereto and means at the opposite end of said line to limit reflection of the waves, whereby to produce directional waves along said line and, by virtue of the oscillation of said vibratile elements in response thereto, the effect of animation therealong.

4. A display device including a background member exhibiting an inscription outline which is to be rendered in apparent animation, a series of vibratile elements, each resiliently mounted to a common support, connected one to the next in an elastic wave transmission line by means through which the vibration of one element is transmitted to successive elements along the line as elastic wave motion, said transmission line extending along the course of said outline, each of said vibratile elements being adapted to oscillate across the corresponding portion of said outline in response to wave motion along said transmission line and in said oscillation to variously modulate the view of said outline portion, and means to impart wave motion to said transmission

line to oscillate said vibratile elements and thereby produce the effect of animation along said outline by virtue of the aggregation of said modulation effects.

5. A display device exhibiting an inscription outline which is to be rendered in apparent animation, a series of vibratile elements connected one to the next in an elastic wave transmission line by means through which the vibration of one element is transmitted to successive elements along the line as elastic wave motion, said transmission line being coextensive with said inscription outline, each of said elements being formed and mounted to vibrate in such fashion as to modulate the appearance of its corresponding portion of said outline when oscillating in response to waves on said transmission line and means to impose wave motion on said transmission line.
- 10 6. A display device including a background member bearing an inscription outline which is to be rendered in apparent animation, a series of vibratile refracting elements connected one to the next in an elastic wave transmission line by means through which the vibration of one element is transmitted to successive elements along the line as elastic wave motion, said transmission line being coextensive with said outline, each of said elements being formed and mounted
- 15 to vibrate in such fashion as to modulate the appearance of its corresponding portion of said outline when oscillating in response to waves on said transmission line and means to impose wave motion on said transmission line.
- 20 7. A display device including a series of vibratile elements connected one to the next in an elastic wave transmission line by means through which the vibration of one element is transmitted to successive elements along the line as elastic wave motion, said transmission line extending along a course definitive of an inscription outline, said elements being so formed that in their oscillation in response to wave motion on said transmission line they individually modulate the appearance of the corresponding portions of the outline depicted and thereby in the aggregate produce the effect of animation along said outline, and means to establish wave motion on said transmission line.
- 25 8. A display device including a series of vibratile elements individually resiliently mounted to a common support and connected one to the next in an elastic wave transmission line by means through which the vibration of one element is transmitted to successive elements along the line as elastic wave motion, said transmission line extending along a course definitive of an inscription outline, said elements being so formed that in their oscillation in response to wave motion on said transmission line they individually modulate the appearance of the corresponding portions of the outline depicted and thereby in the aggregate produce the effect of animation along said outline, and means to establish wave motion on said transmission line.
- 30 9. A display device including a series of vibratile elements connected one to the next in an elastic wave transmission line by means through which the vibration of one element is transmitted to successive elements along the line as elastic wave motion, said transmission line extending along a course definitive of an inscription outline, said elements being so formed that in their oscillation in response to wave motion on said transmission line they individually

modulate the appearance of the corresponding portions of the outline depicted and thereby in the aggregate produce the effect of animation along said outline, means at one end of said transmission line to impart wave motion thereto and means at the opposite end of said line to limit reflection of the waves whereby to produce directional waves, along said line.

10. A display device exhibiting an inscription outline, a plurality of vibratile elements connected one to the next in an elastic wave transmission line by means through which the vibration of one element is transmitted to successive elements along the line as elastic wave motion, said transmission line extending along the course of said outline, each of said elements having a refracting portion formed to variably refract light rays passing from the corresponding portion of said outline to the field of view as it oscillates in response to wave motion on said transmission line and thereby modulates the appearance of said outline portion, and means to establish wave motion along said transmission line to oscillate said vibratile elements and thereby produce the effect of animation therealong.

11. A display device including a background member exhibiting an inscription outline, a plurality of vibratile elements connected one to the next in an elastic wave transmission line by means through which the vibration of one element is transmitted to successive elements along the line as elastic wave motion, said transmission line extending along the course of said outline, each of said elements having a refracting portion formed to variably refract light rays passing from the corresponding portion of said outline to the field of view as it oscillates in response to wave motion on said transmission line and thereby modulates the appearance of said outline portion, and means to establish wave motion along said transmission line to oscillate said vibratile elements and thereby produce the effect of animation therealong.

12. A display device including a background member exhibiting an inscription outline, a plurality of vibratile elements individually resiliently mounted to a common support and connected one to the next in an elastic wave transmission line by means through which the vibration of one element is transmitted to successive elements along the line as elastic wave motion, said transmission line extending along the course of said outline, each of said elements hav-

14

ing a refracting portion formed to variably refract light rays passing from the corresponding portion of said outline to the field of view as it oscillates in response to wave motion on said transmission line and thereby modulates the appearance of said outline portion, and means to establish wave motion along said transmission line to oscillate said vibratile elements and thereby produce the effect of animation therealong.

10 13. A display device including a background member exhibiting an inscription outline, a plurality of vibratile elements connected one to the next in an elastic wave transmission line by means through which the vibration of one element is transmitted to successive elements along the line as elastic wave motion, said transmission line extending along the course of said outline, each of said elements including a lenticular member positioned approximately at focal distance from said outline, and each of said elements being formed to vibrate across said outline when energized by elastic waves on said transmission line, and means to establish wave motion on said transmission line.

15 20 14. A display device including a background member exhibiting an inscription outline, a plurality of vibratile elements connected one to the next in an elastic wave transmission line by means through which the vibration of one element is transmitted to successive elements along the line as elastic wave motion, said transmission line extending along the course of said outline, each of said elements including a lenticular member positioned approximately at focal distance from said outline, and each of said elements being formed to vibrate across said outline when energized by elastic waves on said transmission line, and means to establish unidirectional wave motion on said transmission line.
